United States Patent

Des. 241,439
Patented Sept. 14, 1976

241,439

PORTABLE SPRAY UNIT

Lyle A. Ware, Bloomington, and Lawrence L. Lanerd,
Crystal, Minn., assignors to Graco Inc., Minneapolis,
Minn.

Filed Mar. 14, 1975, Ser. No. 558,208

Term of patent 14 years

Int. Cl. D23—01

U.S. Cl. D23—18

FIG. 1 is a front elevational view of a portable spray unit showing our new design;

FIG. 2 is a bottom plan view thereof;

FIG. 3 is a right side elevational view thereof;

FIG. 4 is a rear elevational view thereof;

FIG. 5 is a left side elevational view thereof; and

FIG. 6 is a top plan view thereof.

The broken line representation of a liquid container in FIG. 3 is for purposes of illustration only.

We claim:

The ornamental design for a portable spray unit, substantially as shown and described.
